(57) **CLAIM**

The ornamental design for a docking station and support, as shown and described.

DESCRIPTION

FIG. 1 is a rear perspective view of the of the docking station and support showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a cross-sectional view taken along line 6-6 of FIG. 5;

FIG. 7 is a top plan view thereof;

FIG. 8 is a cross-sectional view taken along line 8-8 of FIG. 7; and,

FIG. 9 is a bottom plan view thereof.
